STRAIGHTENING TOOL

Edward H. Schultz, Milwaukee, Wis., assignor to
 Blackhawk Mfg. Co., Milwaukee, Wis., a corporation of Wisconsin

Application November 20, 1937, Serial No. 175,688

21 Claims. (Cl. 254—134)

My invention relates generally to improvements in the art of removing dents and other irregularities from sheet metal assemblages, and relates more specifically to improvements in the construction and operation of implements or tools for restoring to normal shape such assemblages as distorted sheet metal automobile bodies or the like.

Generally defined, an object of my present invention is to provide an improved straightening tool for restoring distorted sheet metal assemblages to normal condition, which is simple in construction and highly flexible and effective in operation.

In the art of repairing damaged automobile bodies, it is customary to utilize many varieties of so-called bumping-out tools for the purpose of removing indentations and distortion from sheet metal or other relatively light parts. Each of these prior implements or tools, has ordinarily been formed as a rigid unit especially adapted for a particular class of service, and because of the numerous conditions which are encountered and the varied character of the work, it requires many of these prior individual units in order to enable the repairman to properly repair such assemblages. Since it is preferable to utilize a jack or ram in conjunction with such tools or implements, the latter must be constructed for effective cooperation with the ram, and considerable time and effort is wasted in applying these individual tools to the ram and in substituting one implement for another. The prior bumping-out or straightening tools are therefore relatively impracticable and unsatisfactory, and cannot be used to meet many of the requirements in a most efficient manner and without excessive loss of time.

It is, therefore, a more specific object of my present invention, to provide a new and useful straightening tool which is adjustable so as to most effectively cooperate with indentations of various kinds and shapes, and located in relatively inaccessible portions of a sheet metal assemblage.

Another specific object of the invention is the provision of an improved automobile body repair implement which is conveniently adjustable to meet various conditions of use, without necessarily removing the implement from a jack or ram with which it may be associated.

A further object of my invention is the provision of an improved straightening tool which is simple and durable in construction, and which is especially adapted to remove dents from and to

restore the shape of beads and other distorted parts, in sheet metal roof panels for vehicles such as modern automobile bodies.

Still another specific object of this invention is to provide a repair implement for automobile bodies or the like, which is extremely flexible in use, and which may be manufactured and sold at moderate cost.

These and other specific objects and advantages will be apparent from the following detailed description.

A clear conception of one specific embodiment of my present invention, and of the mode of constructing and of using implements built in accordance with the improvement, may be had by referring to the drawing accompanying and forming a part of this specification wherein like reference characters designate the same or similar parts in the various views.

Fig. 1 is a part sectional side elevation of one of the improved repair implements, showing the toe member thereof in various positions of adjustment in dot-and-dash lines;

Fig. 2 is a part sectional top view of the implement shown in Fig. 1;

Fig. 3 is a transverse section through the improved implement, taken along the line 3—3 of Fig. 1, with the adjusting pivot pin removed;

Fig. 4 is another transverse section through the implement, taken along the line 4—4 of Fig. 2;

Fig. 5 is a side view of the improved adjusting pivot pin of the repair implement;

Fig. 6 is a diagram showing some of the possibilities of adjustment of the improved tool to meet various conditions of use;

Fig. 7 is a diagram showing the mode of utilizing the improved implement for removing a dent in one portion of a sheet metal automobile roof panel;

Fig. 8 is a similar diagram showing the implement being utilized for another class of service;

Fig. 9 is another similar diagram depicting the use of the implement for performing still another type of work; and

Fig. 10 is a further diagrammatic showing of the improved implement being utilized to remove an indentation above the windshield of an automobile body.

While I have shown and described a particular type of repair implement wherein the toe and shank members are relatively adjustable with the aid of a polygonal pivot pin in a specific manner, and the articulatable parts are of a

50

55

particular shape, it is not the intent to thereby unnecessarily restrict the scope of this invention.

Referring to Figs. 1 to 5 inclusive of the drawing, the improved body repair implement or tool shown therein, comprises in general a shank section or member 14 having laterally spaced parallel ears 15 at one end, and a threaded socket 16 at its opposite end adapted for attachment to a jack or ram 17; a spoon or toe member 18 having a supporting portion 19 formed for adjustable disposition between the ears 15 of the shank member 14; and a polygonal pivot pin 20 coacting with the ears 15 and with the toe supporting portion 19 to adjustably position the members 14, 18 relatively to each other.

The shank member 14 is preferably of one-piece sturdy construction, and the alined pin receiving openings 21 formed in the ears 15, are of hexagonal shape, although these openings may be of any other desired polygonal shape adapted to snugly embrace the opposite ends of the locking pin 20. The toe member 18 is also formed of metal and of sturdy structure; and the major portion of this member may be of any desired transverse width, while the supporting portion 19 thereof is adjustably confined between the shank ears 15 and is provided with a tapered heel portion 22 especially adapted for use as a wedge in spreading bent parts. Although the openings 21 in the ears 15 are hexagonal, the corresponding pin receiving opening 23 in the toe portion 19 may be of double hexagonal formation, that is, so formed that the pin 20 may be inserted therein in twelve different positions. This formation of the opening 23 will permit angular adjustment of the toe member 18 about the axis of the locking pin 20 and relative to the shank member 14, by increments of thirty degrees as indicated in dot-and-dash lines in Fig. 1, and this formation is also advantageous in securing fifteen degree adjustments. It will be noted, that by positioning the openings 21 as shown in Fig. 6, with a corner thereof offset from the longitudinal axis 45 of the pushing member 14 by seven and one-half degrees, the toe member 18 may be adjusted relative to the transverse center line of the pushing member 14 by increments of fifteen degrees with the aid of the double hexagonal opening 23 in the supporting portion 19. Such angular adjustments are obtainable because the toe member 18 is freely revolvable about the longitudinal axis of the pushing member 14 as shown in Fig. 6; and after it has been set as shown in solid lines 50 at the left, the member 18 may be revolved about the axis of the push member 14 to position the toe mid-way between the settings thereof illustrated in dot-and-dash lines at the right of Fig. 6. When the members 14, 18 have been set to any predetermined position of adjustment, and the pin 20 is inserted within the alined openings 21, 23 thereof, the two members are firmly locked against relative displacement.

The locking pin 20 is obviously of polygonal shape conforming with the shape of the openings 21, as shown in Figs. 1, 2 and 5, and while this pin snugly engages the openings 21, 23 and is frictionally confined therein, it may also be desirable to lock the pin 20 in place. Such locking may be effected with the aid of a locking ball 24 carried by the supporting portion 19 of the toe member 18 and coacting with an annular recess 25 formed in the medial portion of the pin 20, the ball 24 being reciprocable in a space 26 and being constantly urged toward the opening

23 by means of a compression spring 27 confined within the space 26. The latch ball 24 is of such diameter that it cannot pass through the constricted inner end of the space 26 but can protrude therebeyond and into the recess 25 as shown in Fig. 1, and the space 26 is preferably so located that the ball 24 will always engage a relatively shallow portion of the recess 25 in order to permit the pin 20 to be readily pushed endwise out of the openings 21, 23.

In order to permit the implement to conform with various shapes, the wide overhanging portion of the toe member 18 is preferably curved in a longitudinal direction, and this portion may be either transversely flat as shown in Fig. 4, or one or both of the opposite surfaces thereof may be slightly crowned. The outer surface of the heel portion 22 of the member 18 may also be curved as indicated in Fig. 1, and the sides of the portion 22 may be tapered as shown in Fig. 2. The jack or ram 17 with which the improved implement is ordinarily detachably associated, may be of any suitable type, and as shown herein, this ram 17 is of the hydraulic or fluid pressure actuated type having the end of its plunger 25 screwed into the threaded socket 16 of the shank member 14.

The improved tool or implement is adapted for a variety of uses, and the toe member 18 may obviously be readily adjusted and locked in the desired position of adjustment by merely withdrawing the pin 20 during adjustment and by reinserting this pin in the openings 21, 23 after adjustment has been effected. The device is especially adapted for use in restoring distorted sheet metal body tops, roof panels, or turret tops 28, as shown diagrammatically in Figs. 7 to 10 inclusive. In Fig. 7 the implement is shown in the act of pushing out a downward indentation above the roof rail 29 of the top 28, and with the toe member 18 disposed substantially perpendicular to the common axis of the shank portion 14 and of the ram 17. The ram 17 reacts against the opposite lower corner of the body 30, and the toe member 18 will obviously gradually remove 45 the dent as the ram 17 elongates, so as to effectively restore the distorted portion of the top 28 to normal condition. In Fig. 8 I have shown the tool in the act of removing a downward and inward indentation in the top 28, and in this diagram, the toe member 18 has been adjusted to an oblique angle relative to the longitudinal axis of the shank member 14 and of the ram 17. This oblique disposition of the toe member 18 permits the extreme end thereof to be brought farther 50 over the roof rail 29 and nearer the edge or bead 31 of the roof panel or top 28, thus permitting the ram pressure to more effectively force the dent upwardly as well as outwardly. In Fig. 9 the improved device is shown in the act of 55 straightening a dented bead 31, and in this diagram the toe member 18 has been adjusted into substantial alignment with the common axis of the shank member 14 and ram 17, and the ram has been caused to react against the roof rail 29 at the opposite side of the top 28 so that direct outward pressure can be applied to the distorted bead 31 without interference by the adjacent roof rail 29. Fig. 10 illustrates the use of the improved implement in removing a dent above 70 the header bracket 32 and windshield 33 of an automobile. In this diagram, the toe member 18 is again set at an oblique angle relative to the axis of the shank member 14 and ram 17, so as to most effectively force the dented portion up- 75

wardly without obstruction by the header bracket 32. When utilizing the appliance for other purposes, it may be desirable to adjust the toe member 18 to other angular positions than those specifically illustrated, as for instance to an acute angle adjoining the shank member 14, or to an obtuse angle relative to the member 14 and beyond the position of alignment shown in solid lines in Fig. 1. It will thus be apparent that my improved implement is susceptible of various adjustments for numerous uses, and that the adjustments may be conveniently effected without removing the tool from the ram.

From the foregoing detailed description, it will be obvious that my present invention provides an improved implement or tool which is extremely simple, compact and durable in construction, and which is also highly flexible and efficient in use. The toe member 18 may obviously be quickly and conveniently adjusted so as to insure most effective application of the pressures and consequent restoration of the damaged parts to normal condition. The toe member 18 may also be varied in shape to suit conditions, although the specific shape shown has proven highly practical especially in view of the adjustability herein provided. The adjusting and locking pin 20 need not necessarily be hexagonal, but may be of any desired polygonal or other shape whereby the members 18, 14 are firmly locked in relatively adjusted position, and the latch ball 24 may be replaced by any other means for preventing longitudinal or axial shifting of the pin. The improved device may obviously be readily applied to or removed from the ram 17, and can be manufactured and sold at moderate cost.

It should be understood that it is not desired to limit this invention to the exact details of construction or to the precise uses, herein shown and described, for various modifications within the scope of the claims may occur to persons skilled in the art.

I claim:

1. An implement comprising, a shank member movable along its longitudinal axis and having a polygonal transverse opening, a toe member having its end adjoining said shank member provided with a similarly polygonal opening, and a polygonal pin cooperable with said openings to prevent relative displacement of said members, one of said openings being formed to permit a greater number of angular adjustments of said pin therein than the other.

2. An implement comprising, a shank member having a multi-sided opening therein, a toe member having a multi-sided opening therein alineable with said shank opening, one of said openings having a greater number of sides than the other, and a pin cooperable with said openings to prevent relative displacement of said members.

3. An implement comprising, a shank member having a multi-sided opening therein, a toe member having a multi-sided opening therein alineable with said shank opening, one of said openings having a greater number of sides than the other, a pin cooperable with said openings to prevent relative displacement of said members, and means for locking said pin against displacement along said openings.

4. An implement comprising, a shank member having a pressure applying end and spaced ears at its opposite end, said ears being provided with alined polygonal openings, a longitudinally curved toe member having a supporting portion

disposable between said ears and provided with a more sided polygonal opening alineable with said ear openings, and a polygonal pin cooperable with all of said openings to prevent relative displacement of said members.

5. An implement comprising, a shank member having a pressure applying end and spaced ears at its opposite end, said ears being provided with alined polygonal openings, a longitudinally curved toe member having a supporting portion 10 disposable between said ears and provided with a more sided polygonal opening alineable with said ear openings, a polygonal pin cooperable with all of said openings to prevent relative displacement of said members, and means coating 15 with the medial portion of said pin for preventing axial displacement thereof.

6. An implement comprising, a shank member having a polygonal opening, a toe member having a similarly polygonal opening alineable 20 with said shank member opening, and a pin cooperable with said openings to lock said members in different angular positions, said toe member being reversible relative to said shank member and said openings being formed to permit intermediate angular adjustment of said toe member upon reversal thereof.

7. An implement comprising, a shank member having a hexagonal opening, a toe member having a similarly hexagonal opening alineable 30 with said shank member opening, and a pin cooperable with said openings to lock said members in different angular positions, said toe member being reversible relative to said shank member and said opening in said shank member being 35 offset with respect to the longitudinal axis of said member to permit angular adjustment of said toe member by increments of fifteen degrees upon reversal thereof.

8. An implement comprising, a shank member 40 having a polygonal opening, a toe member having a similarly polygonal opening alineable with said shank member opening, and a pin cooperable with said openings to lock said members in different angular positions, said members being 45 freely rotatable about the longitudinal axis of said shank member and said openings being formed to permit intermediate angular adjustment of said toe member upon alternate reversals thereof with respect to said axis.

9. An implement comprising, a shank member, a toe member, each of said members having a polygonal opening alineable with the opening of the other member, and one of said members having notches in each side of its polygonal opening defining a second similarly polygonal offset opening, and a polygonal pin cooperable with the opening in one of said members and with either of the openings in the other member to lock said members in various positions of adjustment.

10. An implement comprising, a shank member, a toe member, each of said members having a polygonal opening alineable with the opening of the other member, and one of said members having notches in the sides of its polygonal opening defining a second similarly polygonal offset opening, and a pin cooperable with the alined openings to prevent relative displacement of said members.

11. An implement comprising, a shank member, a toe member, each of said members having a hexagonal opening alineable with the opening of the other member, and one of said members having a central 120 degree notch in each side of the opening therein, all of which notches

cooperate to define a second offset hexagonal opening in said member interchangeably alinable with the opening in the other member, and a pin cooperable with the alined openings in 5 said members to lock the latter against relative displacement.

12. An implement comprising, a shank member, a toe member, each of said members having a polygonal opening alinable with the opening 10 of the other member, and one of said members having a central notch in each side of the opening therein, all of which notches cooperate to define a second offset similarly polygonal opening in said member interchangeably alinable with 15 the opening in the other member, and a pin cooperable with the alined openings in said members to lock the latter against relative displacement.

13. An implement comprising, a shank member having a polygonal opening extending across 20 the longitudinal shank axis and the corners and sides of which are disposed out of symmetry with respect to said axis, a toe member having a similarly polygonal opening alinable with said shank member opening, and a pin cooperable with said 25 openings to lock said members in different angular positions.

14. An implement comprising, a shank member having a polygonal opening extending across 30 the longitudinal shank axis and having its corners and sides disposed out of symmetry with respect to said axis, a toe member having a pair of similarly polygonal concentric offset openings 35 interchangeably alinable with said shank member opening, and a pin cooperable with said shank member opening and with either of said toe member openings to lock said members in different angular positions.

15. An implement comprising, a shank member 40 having a hexagonal opening extending across the longitudinal shank axis and having its corners and sides out of symmetry with said axis by seven and one-half degrees, a toe member having a pair of hexagonal concentric openings offset with respect to each other by thirty 45 degrees, and interchangeably alinable with said shank member opening, and a pin cooperable with said shank member opening and with either of said toe member openings to lock said members in successive angular positions each fifteen 50 degrees in advance of the adjacent position of adjustment.

16. In combination, a jack having a movable element freely rotatable about its axis of movement, a shank member carried by and movable 55 with said jack element, a toe member, and a

transverse pivot adjustably connecting said toe member and said shank member, said pivot being formed and cooperating with said members to effect equal increments of angular adjustment about said pivot but differently positioned on 5 the opposite sides of said spindle axis.

17. In combination, a jack having a movable element freely rotatable about its axis of movement, a shank member detachably associated and movable with said jack element, a toe member, and a transverse pivot adjustably connecting said members, said pivot being formed and cooperating with said members to effect successive angular adjustments of said toe member about the pivot axis by equal increments approximately equal to one half of the successive angular adjustments of the pivot.

18. In combination, a jack having a movable element, a shank member carried by and movable with said jack element and being freely rotatable about the axis of movement of said element, and a toe member angularly adjustably associated with said shank member and being rotatable therewith about said axis.

19. In combination, a jack having a movable element, a shank member carried by and movable with said jack element and being freely rotatable about the axis of movement of said element, a toe member, and a pivot pin connecting said members, said pin being formed to effect 30 angular adjustment of said toe member relative to said shank member about an axis intersecting said axis of movement and said toe member being freely revolvable about said axis of movement with said shank member.

20. In combination, a jack having a movable element, a shank member carried by and movable with said jack element and being freely rotatable about the axis of movement of said element, and a toe member carried by said shank 40 member and being freely revolvable with said member about said axis, said toe member being adjustable relative to said shank member about an axis which intersects said axis of movement.

21. In combination, a jack having a movable element, a shank member movable by said jack element and being rotatable about the axis of movement of said element, and a toe member carried by said shank member and extending away from said axis, said toe member being relatively wide and extending laterally beyond the plane of said axis in both directions and also being angularly adjustable relative to said shank in said plane.

EDWARD H. SCHULTZ. 55
